UNITED STATES PATENT OFFICE.

ARTHUR E. BENSON, OF MAGNOLIA, MISSISSIPPI, ASSIGNOR TO DRAPER COMPANY, OF HOPEDALE, MASSACHUSETTS, A CORPORATION OF MAINE.

LOOM-TEMPLE.

SPECIFICATION forming part of Letters Patent No. 774,374, dated November 8, 1904.

Application filed August 26, 1904. Serial No. 222,226. (No model.)

To all whom it may concern:

Be it known that I, ARTHUR E. BENSON, a citizen of the United States, residing at Magnolia, county of Pike, and State of Mississippi, have invented an Improvement in Loom-Temples, of which the following description, in connection with the accompanying drawings, is a specification, like characters on the drawings representing like parts.

10 This invention relates to loom-temples; and it has for its object the production of novel means for effecting an up-and-down tilting movement of the stand of the temple in order to properly adjust the same at a higher or 15 lower position relative to the breast-beam of the loom.

The novel features of my invention will be 20 fully described in the subjoined specification and particularly pointed out in the following claims.

Figure 1 is a perspective plan view of a loom-temple embodying one form of my present invention. Fig. 2 is a right-hand side elevation thereof, the shank of the temple-head being broken off. Fig. 3 is an enlarged side elevation, partly broken out, of the tilting plate-slide; and Fig. 4 is a detail thereof, partly in plan and partly on the horizontal line 4 4, Fig. 3.

30 In Fig. 1 the longitudinally-slotted base-plate *b*, adapted in practice to be secured to the breast-beam *B*, Fig. 2, the temple-head *h*, having an attached shank *h'* slidably mounted in the stand *A* and normally projected by 35 a spring, (not shown,) may be and are all of well-known construction.

Usually the stand and base-plate are connected by a plate-slide which is longitudinally adjustable on the base-plate, and the stand is 40 adjustable fore and aft on the stand by means of the slotted flange *a* on the stand. When it is found necessary to tilt the temple in order to raise or lower the temple-head, it is common practice to insert pieces of paper or 45 leather under one or the other edge of the base-plate, an unmechanical expedient and more or less inefficient. In my present invention I have made the plate-slide capable of ready and accurate adjustment to tilt the

temple without interfering with the usual lateral or fore-and-aft adjustments referred to. To this end the plate-slide is made in two parts pivotally connected and comprising a body portion *1*, having upturned transverse ears *2* and an extension *3*, the body and extension resting upon the base-plate *b* and being adjustably connected therewith by a clamp-screw *4*, Fig. 1, and a top *5*. The top has depending ribs *6*, which project loosely between the ears *2* and which are pivotally connected therewith by a pin *7*, so that the top can be tilted upon the same as a fulcrum. The stand *A* is seated upon the top and is secured thereto by set-screws *8*, Figs. 1 and 2, which extend through the slotted flange *a*, so that the stand can be adjusted fore and aft upon the plate-slide. In order to readily vary the inclination of the top of the latter, and thereby raise or lower the temple-head, I have provided a rotatable cam *9*, mounted in the ears *2* and entering slots *10* in the ribs *6* of the top. This adjusting-cam is made conveniently by pinning the sleeve *9* eccentrically on a bolt *11*, which is rotatably mounted in holes in the ears *2*, the head *12* of the bolt being shown as nicked, while a nut *13* serves to clamp the cam when set.

By means of a screw-driver the cam can be turned when the nut *13* is loosened to raise or lower the front end of the top, changing the inclination of the temple-stand, and thereby the vertical position of the temple-head, as will be manifest. A very accurate angular adjustment can thus be effected entirely independent of the fore-and-aft or lateral adjustment of the temple-stand, the plate-slide thus constituting an adjustable tilting connection between the stand and the base-plate.

Having fully described my invention, what I claim as new, and desire to secure by Letters Patent, is—

1. In a loom-temple, a base-plate, a stand, a plate-slide connecting them and adjustable longitudinally on the base-plate, and means on said plate-slide to change the inclination of the top thereof and thereby tilt the stand.

2. In a loom-temple, a base-plate, a stand, a plate-slide having a tiltable top adapted to

be rigidly connected with the stand, means to vary the angle of said top with relation to the plate-slide, and a connection between the latter and the base-plate.

5. 3. In a loom-temple, a base-plate, a stand, a two-part, pivotally-connected plate-slide the parts of which are adapted to be rigidly connected with the stand and base-plate respectively, and a cam rotatably mounted on one part and adapted to coöperate with the other part of the plate-slide, to effect relative pivotal movement of said parts and thereby vary the inclination of the stand.
10. 4. In a loom-temple, a stand, a plate-slide

comprising a body portion having upturned sides, a top pivotally mounted thereon between the sides, and a cam rotatably mounted in said ears and operatively connected with the top, to tilt the same, and means to adjustably connect the temple-stand with the top 15 20 of the plate-slide.

In testimony whereof I have signed my name to this specification in the presence of two subscribing witnesses.

ARTHUR E. BENSON.
